UNITED STATES PATENT OFFICE.

KIRJATH ARBA GODWIN, OF SALEM, NEW JERSEY.

TOOL FOR FINISHING HEADS OF BOTTLES.

1,092,569.

Specification of Letters Patent.

Patented Apr. 7, 1914.

Application filed April 8, 1912. Serial No. 689,151.

To all whom it may concern:

Be it known that I, KIRJATH ARBA GODWIN, a citizen of the United States, residing in the city and county of Salem, State of

5 New Jersey, have invented a new and useful Tool for Finishing Heads of Bottles, of which the following is a specification.

10 My invention relates to a new and useful tool for finishing the heads of bottles, and consists of means for forming a uniform circumference of the heads.

It further consists of means for forming a screw thread on the heads.

15 It further consists of novel means adapted to be actuated to force the glass into a former.

It further consists of other novel features of construction, all as will be hereinafter fully set forth.

20 For the purpose of illustrating my invention I have shown in the accompanying drawings one form thereof which is at present preferred by me, since the same has been found in practice to give satisfactory and 25 reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a tool for finishing the necks of bottles embodying my invention. Fig. 2 represents a 35 longitudinal sectional view thereof on an enlarged scale partly broken. Fig. 3 represents a longitudinal sectional view showing certain of the parts in a different position from that shown in Fig. 2. Fig. 4 represents 40 a sectional view on line $x-x$, Fig. 3. Fig. 5 represents an elevation of a neck of a bottle showing the screw threads and shoulder formed thereon. Fig. 6 represents a sectional view of the head and neck of a bottle 45 showing an enlargement or shoulder thereon and without the screw threads.

Similar numerals of reference indicate corresponding parts in the figures.

Referring to the drawings: 1 designates 50 a block or tail-piece to which is adjustably connected in any suitable manner the rod 2, which, as here shown, is provided with threads 3 and which passes through a suitable bore or opening 4 in the block 1, and to 55 which it is connected by means of the nuts 5 and 6. Carried by said rod is a mandrel

7, which, as here shown, is tapering, but which may be of any suitable size or shape, depending upon the opening desired in the bottle.

60 8 designates a sleeve suitably secured to the rod 2 and carrying the head or plate 9.

10 designates a former of any suitable shape, which is rotatably mounted, as here shown, upon a suitable portion of the sleeve 35 8 and between which are the ball bearings 11, which are situated in suitable race-ways which are formed respectively in the head 9 and former 10, it being understood that the said former is provided with a suitable 70 face which bears against the end of the mandrel 7, and that the flange 12 of the former 10 encircles the mandrel, or a suitable portion thereof, forming a space 13 therebetween into which the glass is forced. 75 I preferably desire to employ threads upon the inner wall of said flange 12 to provide screw threads upon the heads of the bottles.

14 designates arms pivotally mounted, as here shown upon the block 1, which extend 80 exteriorly of said former 10, and to which are removably connected the jaws 15 each having a shoulder 16 inwardly facing, that is facing the mouth of the former.

17 designates springs suitably secured and 85 having portions thereof bearing upon the arms 14 in order to hold the same in open or expanded position and to return the same thereto, it being understood and noted more particularly from Fig. 3 that the jaws 15 90 are situated at a distance beyond the mouth of said former and on opposite sides thereof and that in their normal or open position they are a greater distance apart than the diameter of the mouth of the former in 95 order to permit free entrance of the glass into the former, but that when suitably actuated, they are moved to a position partly across said mouth, as seen in Fig. 2. The jaws are comparatively wide, and their op- 100 posed faces are curved to impart the proper curved outlines to the neck of the revolving bottle and to properly distribute the plastic glass of the head and neck. The stationary mandrel supports the neck from within, and 105 the rotatable former will rotate with the bottle and allow the shoulders of the jaws, which are held stationary, to crowd the plastic glass into the former to impart the desired shape to the head of the bottle. I 110 have provided means for normally locking said former 10 against rotation, which lock-

ing means are adapted to be actuated at the proper time to release said former to permit rotation thereof, and, as here shown, I have pivotally mounted an elbow lever 18 on the 5 head 9, one arm of which lever is in suitable connection with one of the arms 14 in order to be actuated thereby, while the other arm of the said lever 18 is in suitable connection with a pin 19 which is adapted to engage with one of a plurality of suitable recesses 20 provided in the former 10. As 10 here shown, the pin 19 is movable in a suitable opening in the head 9.

21 designates stops, here shown as set 15 screws, carried by the arms 14 and which are adapted to contact with the edge of the head 9 in order to limit the inward movement of said arms 14 and so the jaws 15. Suitable means is provided for assisting in 20 guiding the arms 14 in their movement, and as here shown, I have provided a plate 22 suitably connected with the head 9 and provided with a slot 23 in which the arms 14 move. It will be understood that the inner 25 face of the jaws 15 may be formed of any suitable shape, depending upon the character of the neck of the bottle desired.

In the construction shown in Fig. 6, I have shown a bottle with the head plain and 30 with an enlargement or shoulder 24 formed thereon, the inner wall of its flange 12 of the former in this case, being without threads and the jaws employed being suitably formed to correspond to the shape of 35 enlargement and of the neck.

The operation of the device will be readily apparent, the jaws and arms being in the position seen in Figs. 1 and 3 and the operator grasping the tool will force the snap 40 or bottle partly formed upon the mandrel 7, which thus enters the mouth of the bottle, and the hot or plastic glass forming the head is directed into the former, whereupon the operator by actuating the arms 14 and 45 by overcoming the tension of the springs 17 will bring the jaws 15 against the neck of the bottle. At the same time, by the actuation of the arms 14, the lever 18 is rocked on its pivot and removes the pin 18 from engagement with the recess 20 in which it is 50 seated on the former, so that the latter is free to rotate with the bottle or snap, which rotation is imparted by the operator so that the shoulders 16 of the jaws will force a 55 suitable amount of the hot glass into the space 13 between the mandrel and the flange 12 of the former 10, whereby it will be understood that a positive uniformity of the circumference of the finish or head of each 60 bottle is obtained and an enlargement or

shoulder 24 is formed. When the former is provided with threads the jaws will act to force the plastic glass not only into the former but also into the threads thereon, so that the head of the bottle is formed with a 65 shoulder or enlargement 24 and with screw threads 25, while the neck is shaped by the inner faces or walls of the jaws 15, as will be evident. When the operator releases the jaws 14 at the proper time, the springs 17 70 open or return the jaws 15 to their normal position, the former 10 is again locked, and the operator can unscrew the bottle from the said former, as will be evident.

It will of course be understood that the 75 glass forming the blank or bottle is in suitable plastic condition when the tool above described is applied thereto.

From the above it will be understood that I have provided a tool which is simple in 80 construction, easy in operation, positive in its action and produces an article which has heretofore not been obtained by mechanical means.

Having thus described my invention, what 85 I claim as new and desire to secure by Letters Patent, is:—

1. In a device of the character stated, a stationary mandrel adapted to contact with the inner wall of the mouth of the bottle to 90 form the same, a rotatable head-shaping former at the inner end of the said mandrel to shape the upper edge of the mouth and the locking means on the exterior of the head of the bottle, means adapted to be actuated to force the glass into said former, and means for normally locking said former against rotation and adapted to be actuated to release said rotatable former, when said forcing means is actuated. 100

2. In a device of the character stated, a stationary mandrel adapted to contact with the inner wall of the mouth of the bottle to form the same, a rotatable, internally threaded former at the inner end of said mandrel to shape the upper edge of the mouth of the bottle and the screw threads on the exterior of the bottle, jaws adapted to be actuated to force the glass into said former, means for normally holding said jaws in and returning the same to open position, and means for normally locking said former against rotation and adapted to be actuated to release said rotatable former, when said jaws are actuated. 110
